UNITED STATES PATENT OFFICE.

ERNST ZACHRISON, OF CHICAGO, ILLINOIS.

LIME-SPREADING MACHINE.

Application filed June 11, 1924. Serial No. 719,230.

This invention relates to a lime spreading machine.

One of the objects of the invention is to provide a simple and improved form of 5 lime spreading machine.

A further object of the invention is to provide an improved means in connection with a lime spreading device for pulverizing or breaking up the lumps of lime prior 10 to discharging the lime from the hopper or container.

A still further object of the invention is to provide an improved form of distributing mechanism for a lime spreading machine.

15 A still further object of the invention is to provide an improved form of hopper or container for a lime spreading machine in which the lime is directed by the construction of the hopper to a centrally located 20 opening in the hopper from where it is discharged onto my improved distributing mechanism.

These and other objects are accomplished 25 by providing a construction and an arrangement of the various parts in the manner hereinafter described and particularly pointed out in the appended claim.

Referring to the drawings, Fig. 1 is a side 30 elevational view of my improved lime spreading mechanism.

Fig. 2 is a cross sectional view taken on the line 2—2 in Fig. 1, and

Fig. 3 is a fragmentary cross sectional view taken on the line 3—3 in Fig. 2.

35 In carrying out my invention I have shown the same in connection with a main frame 10 which comprises two horizontally positioned side frame members 11 which have secured on their opposite ends transversely extending forward and rearward frame members 12 and 13, respectively. These frame members 11, 12 and 13 are arranged with respect to each other so as to form a substantially rectangular frame work 40 which is adapted to receive and support therein a hopper 14 of a construction hereinafter described. Secured to the front frame member 12 are two downwardly extending or inclined supplemental frame 45 members 15 which have their forward ends supported on a forward steering truck 16, which, in turn, is provided with the usual wheels 17. The rearward frame member 13 is provided with similarly arranged supplemental frame members 18 which have their 50 lower rearward ends mounted on a suitable

axle 19. The axle 19 is provided with the usual carrying wheels 20. Journaled on a hub portion (not shown) of one of the carrying wheels 20 is a drive sprocket 21. The 60 drive sprocket is provided with a clutch member (not shown) which is adapted for operatively connecting the sprocket 21 with one of the carrying wheels 20. The clutch control member for operatively connecting the drive sprocket 21 with one of the carrying wheels 20 is a forwardly extending rod 22 which extends forwardly to the forward end of the hopper in a manner so as to be 65 within easy reach of the operator for throwing the clutch in and out of engagement. This clutch mechanism is of any well known construction and for this reason it is believed that a more detailed description or illustration of the construction is unnecessary. 70

75 One of the important features of my invention is the construction of my improved hopper which is provided with two vertically extending sides 23, one of which is provided with a hinged portion 24 which swings about 80 hinges 25 for lowering one side of the hopper when the hopper is being loaded with lime. The hopper is provided with forwardly and rearwardly inclined bottoms 26 and 27, respectively, which directs the lime 85 as it is being distributed toward the transverse center of the hopper. The rearwardly inclined bottom 27 of the hopper is curved slightly at the transverse center of the hopper as shown at 28 and terminates as shown 90 at 29 on a line substantially on the transverse center of the hopper. The forwardly inclined bottom 26 of the hopper terminates as shown at 30, thereby forming a transverse longitudinal slot or opening 31 in the 95 bottom of the hopper. Adjustably mounted on the forwardly inclined bottom 26 is an adjustable bottom member 32 which can be regulated or adjusted for controlling the size of the opening in the bottom of the hopper by means of two rods 33, one of which is shown. The rods 33 are provided with crank portions 34 which are within easy reach of the operator and have their lower ends adjustably secured in brackets 34 by threaded engagement therewith. The lower ends of the rods 33 are preferably pivotally secured as shown at 35 in any well known manner to the adjustable bottom 32. Mounted in the bottom adjacent the opening 31 and extending across the hopper is a roller 36 which is preferably provided with longi-

tudinally extending peripheral ribs 37 for pulverizing and breaking the lumps of lime fed between the adjustable bottom 32 and the roller as the roller feeds the lime through the opening 31 in the bottom of the hopper. The roller 36 is preferably a steel roller and is operatively driven by a chain 38 which is geared to a sprocket 39 secured to the shaft 40 of the roller. The chain 38 is trained about a sprocket 41 which is secured to a shaft 42 rotatably mounted in an L-shaped bracket 43 which is secured by means of bolts 44 to the main frame 10 and the hopper 14. The L-shaped bracket 43 is further secured in position by a brace 45. The sprocket 41 derives its power through one of the carrying wheels 20 of the lime spreading machine by means of a drive chain 46 which is geared to a drive sprocket 21. The drive chain 46 is trained on a sprocket 47 which is secured to the shaft 42.

Another important feature of my invention is the provision of a novel means for evenly distributing the lime as it is discharged from the opening 31 in the hopper. This distributing mechanism comprises two oppositely disposed brushes 48 and 49 which are preferably made of wire bristles in the form of rollers. The brush 49 is secured to and adapted to rotate with the shaft 42. The shaft 42 is provided with a spur gear 50 which meshes with a similar spur gear 51. The gear 51 is secured to a shaft 52 which rotatably supports and operatively drives the brush 48 in co-operation with the brush 49 for evenly distributing the lime as it is fed by the roller 36 through the opening 31 of the hopper 14.

Another important feature of my invention is the provision of means for adjusting the brush 48 with respect to the brush 49. This comprises an adjusting screw 53 which is in threaded engagement with a boss 54 formed integrally with the L-shaped bracket 43. The rear end of the adjusting screw 53 is pivotally secured to an adjustable bearing 55 which is slidably mounted in a horizontal slot 56 formed in the horizontal portion of the L-shaped bracket 43. It will be understood, of course, that there are two such L-shaped brackets secured on the opposite sides of the hopper which are provided with corresponding adjustable parts as above described and that when it is found necessary to vary the pressure between the brushes 48 and 49 that the ad-

justable screw 53 may be adjusted so that these brushes may be relatively adjusted with respect to each other in order that a better distribution of the lime may be had. It will be noted also that the pressure between these brushes 48 and 49 may be varied so that the pulverizing action of the brushes on the lime may be had in order to adapt the brushes to the condition of the lime.

In the operation of my improved lime spreading machine it will of course be understood that the lime is loaded or placed in the container or hopper 14 and that when the clutch is shifted so that one of the carrying wheels 20 operatively drives the brushes 48 and 49 as well as the feeding or pulverizing roller 36 that the lime is discharged by the action of the feed roller through the transverse opening 31 in the hopper. And as the lime is discharged on the revolving brushes 48 and 49 it is further pulverized and distributed over a wide area of the ground by reason of the revolving action of the brushes.

While in the above specification I have described one embodiment which my invention may assume in practice, it will, of course, be understood that the same is capable of modification and that modification may be made without departing from the spirit and scope of my invention as expressed in the following claim.

What I claim as my invention and desire to secure by Letters Patent is:

A lime spreading machine comprising a frame mounted on carrying wheels, a hopper mounted on said frame having a transverse opening in the center thereof, said hopper having its bottom inclined toward the center thereof for conveying the lime to said opening, a roller positioned wholly within said hopper and adapted to be moved in a direction parallel to said bottom member adjacent said opening for pulverizing the lumps of lime and for feeding the lime through said opening, oppositely disposed brushes positioned adjacent to and parallel with said roller and outside said hopper for distributing the lime discharged by said roller, and an adjustable bottom member positioned inside of said hopper for regulating the size of said opening.

In testimony whereof I have signed my name to this specification, on this 6th day of June A. D. 1924.

ERNST ZACHRISON.
